S. J. Patterson

UNITED STATES PATENT OFFICE.

STEPHEN J. PATTERSON, OF BRIDGEPORT, CONNECTICUT.

IMPROVEMENT IN APPARATUS FOR TANNING.

Specification forming part of Letters Patent No. 33,448, dated October 8, 1861.

To all whom it may concern:

Be it known that I, STEPHEN J. PATTERSON, of the city of Bridgeport, in the county of Fairfield and State of Connecticut, have invented a new and useful Machine for Tanning Leather; and I do hereby declare that the following is a full and exact description thereof, reference being had to the accompanying drawing, and to the letters of reference marked thereon.

The nature of my invention consists in placing upon the top of the vat containing the liquor in which leather is to be tanned a rocking frame containing a number of slats upon which the hides are to be hung, so that the hides may remain suspended in the liquor and may keep the liquor agitated whenever said rocking frame is kept in motion. My invention further consists in connecting to said rocking frame one or more paddles, which shall move with said frame near the bottom of the vat and agitate the liquor in said vat.

My invention will be more fully understood by reference to the accompanying drawings, in which—

A represents the ordinary vat used by tanners, while the dotted lines of the drawing are intended to expose to view the interior arrangements thereof. Across the center of the vat and on the top thereof I place the piece of timber B, the ends of which rest upon the sides of the vat and are fitted so as to turn in boxes placed at C C. To this cross-piece B, I fit the frame D, which is made just large enough to fit the inside of the vat and allow sufficient room to play up and down. This frame is made of wood of about two by seven inches, and has notches cut in the upper part of the side sticks, as shown at E E, so that the wooden slats F F may be fitted in them. The movable wooden pieces G G are placed over the ends of the slats F F and are held down to their place by the buttons H H. By turning said wooden buttons and removing the sticks G G the slats may be removed from the frame, if placed in it, at pleasure. The frame D is hung just far enough below the top of the vat to allow the liquor in the vat to come above the top of the slats F F when

said frame is in a horizontal position. I represent paddles which are connected firmly to the frame D by means of the arms J J. There is also secured to the frame D a lever-arm K, which is to be used by the hand to give the frame a rocking motion.

When I desire to tan hides by and with the aid of this invention, I take out the slats F F from the frame D and hang one hide over each slat, so that the ends of the hides may not rest upon the bottom of the vat. I then place the slats with the hides thereon in the frame and secure them in their position. Whenever it is necessary to agitate the liquor in the vat it is only necessary to move the lever K, and thus impart a rocking motion to the frame D. It is found that the movement of the frame and the hides hanging upon the slats is sufficient to agitate the liquor to the necessary degree, although I have in this case added the paddles I I in order to increase the agitation, if desired.

With the use of this machine it is not necessary to remove the hides from the vat until they are fully tanned, while the amount of time saved in tanning the leather is less than half of the time required by the common method, any at the same time a great saving in labor is effected.

I am aware that hides have heretofore been suspended from slats in frames placed over vats, and I do not therefore claim that device generally; but

What I claim as my invention, and desire to secure by Letters Patent, is—

1. Attaching to the top of a tanner's vat a frame hung upon its center, substantially as described, so arranged and constructed that the hides to be tanned may be suspended from said frame and may be set in motion by rocking said frame upon its center.

2. In combination with the rocking frame, the paddles I I, substantially as and for the purpose described.

STEPHEN J. PATTERSON.
